[57] **CLAIM**

The ornamental design for the bottle carrier, as shown and described.

DESCRIPTION

FIG. b 1 is a front elevational view of the bottle carrier showing my new design, the broken strap being indicative of indeterminate length;

FIG. 2 is a rear elevational view thereof, the broken strap being indicative of indeterminate length and the broken line showing of a bottle for illustrative purposes only and forming no part of the claimed design;

FIG. 3 is a left side elevational view thereof, the broken strap being indicative of indeterminate length;

FIG. 4 is a right side elevational view thereof;

FIG. 5 is a top plan view thereof;

FIG. 6 is a bottom plan view thereof; and,

FIG. 7 is a perspective view thereof, the broken strap being indicative of indeterminate length.
